UNITED STATES PATENT OFFICE.

ADOLF WEISS AND EMIL NAGEL, OF FREDERICKSBURG, TEXAS.

STONE-DRILLING MACHINE.

No. 882,805.

Specification of Letters Patent. Patented March 24, 1908.

Application filed May 22, 1907. Serial No. 375,032.

To all whom it may concern:

Be it known that we, ADOLF WEISS and EMIL NAGEL, citizens of the United States, residing at Fredericksburg, in the county of Gillespie and State of Texas, have invented certain new and useful Improvements in Stone-Drilling Machines, of which the following is a full, clear, and exact description, reference being had to the accompanying drawings, forming a part hereof.

Our invention has relation to improvements in stone-drills; and it consists in the novel construction and arrangement of parts more fully set forth in the specification and 15 pointed out in the claims.

In the drawings, Figure 1 is a side elevation of the drill; Fig. 2 is a horizontal section on the line 2—2 of Fig. 1; and Fig. 3 is an enlarged transverse vertical section on line 3—3 20 of Fig. 2.

The object of our invention is to construct a machine for drilling granite, marble and stone generally to the tool of which water will be automatically fed during the drilling 25 operation; one which will require a minimum effort to operate, and one possessing further and other advantages better apparent from a detailed description thereof which is as follows:

30 Referring to the drawings, F represents a suitable frame having basal lugs 1, 1, provided with screws 2 for securing the same to any suitable support. Mounted in suitable bracket arms 3, 3, at the free end of the frame 35 is a rock-shaft 4 provided with a central laterally projecting arm 5 from the end of which depends pivotally a link 6 whose lower end is coupled pivotally to the adjacent end of a pedal bar 7 provided with a foot rest 40 8. The pedal 7 is hinged at a convenient point near the base of the frame F. The rear end of the rock-shaft 4 terminates in an arm 9 which is loosely coupled to the upper end of a vertically reciprocating connecting 45 rod 10 passing loosely through guide-brackets 11, the rod being normally depressed by a spring 12 confined between the brackets, one end of the spring bearing against the upper bracket, and the lower against a fixed collar 50 13 carried by the rod. The lower end of the rod 10 is pivotally coupled to the end of a crank-arm 14 at the end of the spindle 15 of an ordinary rock-valve confined in the valve-casing 16 communicating with an outlet tube 55 17 leading from the bottom of a water tank A supported on a plate 18 resting on legs 19

the plate 18 being coupled in any mechanical manner to the general supporting frame F. Leading from the valve-casing 16 is a spout 20 which discharges the water to the cutter of 60 the tool t. The tool-shank is loosely mounted in bearings 21, 21 identified with the main frame, the upper extension t' of the shank being polygonal or square in cross section and receiving the blows of the sledge which drives 65 the cutter into the stone being drilled. The tool is normally held disengaged from the surface operated on, by an expanding spring 22 one end of which bears against the ring or boss 23 formed on the plate 18, the upper end 70 of the spring bearing against a collar 24 carried by the tool-shank.

Carried at the outer end of the shaft 4 is an arm or lug 25 to which is secured an advancing pawl 26, said pawl engaging the teeth of 75 a horizontally rotatable ratchet disk 27 loosely secured to the extension t of the tool-shank. To prevent accidental backward rotation of the parts a locking pawl or check-pawl 28 is conveniently mounted on the 80 frame. The locking pawl too, holds the ratchet 27 to its bearing 21 during the vertical reciprocations which the tool-shank necessarily partakes of under the blows of the sledge in one direction, and the spring 22 in 85 the opposite direction in the operation of the machine. S, represents a seat for the operator.

The operation is as follows: The operator seated on the seat S operates the pedal 8 90 thereby imparting a rocking motion to the shaft 4 as is obvious, the arm 5 being depressed with a downward movement of the pedal, and automatically rising to its return position under the action of the spring 12 95 which through the collar 13 is virtually coupled to the arm 9 pointing in a direction opposite to the arm 5. So that as arm 5 is depressed, the arm 9 is raised, the latter through the connections described rocking 100 the stem 15 of the water-cock or valve and allowing the water to escape from the tank A through the spout 20 to the cutter of the tool t. With each oscillation of the shaft 4 the pawl 26 rotates the disk 27 and hence the 105 tool t. As the latter thus periodically rotates, it is struck with a sledge whose blow is directed against the end t', and thus the drilling proceeds. Obviously, and as shown in Fig. 2 of the drawings, the disk 27, passed 110 over the polygonal extension t' of the tool, is capable of imparting rotation to said tool;

but the part t' is only loosely inserted through the disk to permit the tool to partake of independent vertical movements necessarily imparted to it under the action 5 of the sledge blows. The collar 24 of course is either keyed or shrunk on the tool t or secured in any well known mechanical manner and no special illustration thereof is here necessary.

10 Having described our invention, what we claim is:

In a drill, a suitable rotatable drilling tool, a spring for normally disengaging the same from the surface operated on, a ratchet carried by the tool-shank, a rock-shaft, a pawl coupled to the shaft and engaging the ratchet, a water-tank, a spout leading from the tank to a point in proximity to the cutter of 15

the tool, a rock-valve controlling the flow of water through the spout, a pedal coupled to 20 the rock-shaft, a connecting-rod interposed between the rock-shaft and rock-valve, and a spring coupled to the connecting rod for actuating the same in one direction and impelling the rock-shaft in a corresponding 25 direction, the pedal serving to actuate the shaft in the opposite direction, the parts operating substantially as, and for the purpose set forth.

In testimony whereof we affix our signatures, in presence of two witnesses.

ADOLF WEISS.
EMIL NAGEL.
